The ornamental design for piezoelectric semiconductor element, as shown and described.

DESCRIPTION

FIG. 1 is a front view of the inventive design for a piezoelectric semiconductor element;
 FIG. 2 is a top view of the inventive design of FIG. 1;
 FIG. 3 is a bottom view of the inventive design of FIG. 1;
 FIG. 4 is a left side view of the inventive design of FIG. 1;
 FIG. 5 is a right side view of the inventive design of FIG. 1;
 FIG. 6 is a rear view of the inventive design of FIG. 1;
 and,
 FIG. 7 is a cross-section view of the inventive design of FIG. 1 taken along the lines 7—7 of FIG. 6.
